UNITED STATES PATENT OFFICE.

JOHN BEAZLEY, OF LAPORTE, TEXAS.

RAILROAD-TIE.

SPECIFICATION forming part of Letters Patent No. 735,198, dated August 4, 1903.

Application filed December 30, 1902. Serial No. 137,205. (No model.)

To all whom it may concern:

Be it known that I, JOHN BEAZLEY, a citizen of the United States, residing at Laporte, in the county of Harris and State of Texas, have invented certain new and useful Improvements in Railroad-Ties; and I do declare the following to be a full, clear, and exact description of the invention, such as will enable others skilled in the art to which it appertains

10 to make and use the same.

My invention is an improved railroad-tie; and it consists in the peculiar construction and combination of devices hereinafter fully described and claimed.

15 The object of my invention is to provide an improved railroad-tie which is adapted to be manufactured at slight cost, is exceedingly strong and durable, and is provided with means for effectually securing the rails so

20 that the same are prevented from spreading.

In the accompanying drawings, Figure 1 is a perspective view of a railway-tie embodying my improvements, showing the same in position to support the rails. Fig. 2 is a top

25 plan view of a section of a railway provided with my improved tie, showing alternate ties disposed in reverse relation end to end to effectually lock the rails against spreading.

Fig. 3 is a detail transverse sectional view of 30 one of my improved ties, and Fig. 4 is a detail longitudinal sectional view of the same.

My improved railway-tie comprises a base 1 and sides 2, which rise from the upper side thereof and are formed integrally therewith,

35 the tie being made either of wrought or cast steel, iron, or other suitable metal, as may be preferred. The sides 2 of the tie are formed on their upper sides with locking lips or

40 flanges 3, adapted to engage one side of the base-flanges of the rails *a*, said locking lips or flanges being at suitable distances from the ends of the tie and all extended in the same direction, so that by reversing the ties

45 alternately end for end, as shown in Fig. 2, the said locking lips or flanges 3 of the respective ties will engage opposite sides of the

base-flanges of the rails, so that the rails will be effectually prevented from spreading, as will be understood. Each tie is furthermore

50 provided at the points beneath the rails with cross-plates 4, which are disposed to engage the under sides of the rails and connect the

sides 2 of the tie together near their upper edges, said cross-plates being preferably welded to the sides and serving to effectually 55 brace and strengthen the tie transversely, as will be understood. Under the said cross-plates 4 are vertically-disposed cross-bars 5, which are also made, preferably, of steel or iron, extend transversely across the tie, have 60 their ends preferably welded to the sides 2 of the tie, have their upper edges preferably welded to the under sides of the cross-plates 4, and have their lower edges preferably welded to the base-plate 1. Notches 6 are 65 formed in the under sides of the cross-bars 5 to prevent water from accumulating in the ties and to permit the same to drain therefrom. I furthermore provide each of my improved ties with pivoted locking-dogs 7, which 70 are disposed opposite the lips or flanges 3 and are adapted to engage the sides of the base-flanges of the rails opposite those engaged by the said lips or flanges 3. The said pivoted locking-dogs are detachably connected to the 75 tie by removable pivot-pins 8, which are placed in openings 9, with which the sides 2 of the tie are provided, and when the said locking-dogs are engaged with the base-flanges of the rails the same are locked in 80 such engaged position by removable key bolts or pins 10, which are adapted to be placed in and removed from openings 11, with which the tie is provided.

From the foregoing description, taken in 85 connection with the accompanying drawings, the construction, operation, and advantages of my invention will be readily understood, it is thought, without requiring a more extended explanation.

Various changes in the form, proportion, and the minor details of construction may be resorted to without departing from the principle or sacrificing any of the advantages of the invention.

Having thus described my invention, what I claim as new, and desire to secure by Letters Patent, is—

A railway-tie having side flanges formed with locking-lips on their upper sides to engage one side of the base-flange of each rail, cross-plates connecting the side flanges together and lying under the rails, locking-dogs pivotally mounted between the side flanges,

adapted to engage the opposite sides of the base-flanges of the rails and to lock against the cross-plates when so engaged, and removable locking-pins in openings in the said flanges and bearing against the pivoted dogs, said pivoted locking-dogs coacting with the locking-lips of the side flanges to secure the rails, substantially as described.

In testimony whereof I have hereunto set my hand in presence of two subscribing witnesses.

JOHN BEAZLEY.
